MAGNIFYING GLASS RENTING DEVICE

Frank Brodsky, New York, N. Y.

Application October 12, 1937, Serial No. 168,543

1 Claim. (Cl. 194—83)

This invention relates to automatic vending machines and has for its main object to provide a device through which a magnifying glass may be rented for a limited use.

5 Another object of this invention is to provide a device of this character in which the magnifying glass normally will be locked in an inoperative position, adapted to be freed for such limited use by an appropriate coin being dropped into a receiving element in the machine; the magnifying glass still remaining securely attached to the machine against theft, and automatically returning to its locked inoperative position when released by the user.

10 15 Other objects of this invention will be apparent as the specification of the same proceeds.

In the drawings forming a part of this specification and accompanying the same:

Fig. 1 is a fragmentary sectional detail of one 20 embodiment of my invention;

Fig. 2 is a sectional fragmentary detail, the section being taken on the line 2—2 of Fig. 1 and showing the magnifying glass in an inoperative position;

25 Fig. 3 is a similar section to that of Fig. 2, showing the magnifying glass in a released position;

Fig. 4 is a sectional detail showing the essential operative parts of another embodiment of my invention;

30 Fig. 5 is a sectional plan view of said second embodiment, the section being taken on the line 5—5 of Fig. 4;

Fig. 6 is a similar section to that of Fig. 5, showing said second embodiment in an open position, 35 the magnifying glass being ready for use, portions of the mechanism having been omitted;

Fig. 7 is a perspective view of a rocking shaft, and a sleeve therearound, used in the embodiment of my device shown in Figs. 4 to 6; and

40 Fig. 8 is a fragmentary detail of said embodiment.

Referring now to the drawings more in detail by characters of reference, the coin operated automatic magnifying glass renting device is housed 45 in a casing, generally indicated by the numeral 10.

In the embodiment shown in Figs. 1 and 2 said casing may have a front wall 11, on the inside of which is arranged a chute 12 of any usual construction to receive and guide the coin, having 50 an opening or mouth 13 outside of the casing 10 into which the coin may be dropped.

The coin 14 dropped into said chute will descend to the bottom thereof and will come to rest on the projecting part 15 of a rocking plate 55 member 16, which normally is kept in the posi-

tion shown by the full lines in Fig. 1 by the action of the spring 17, its movement being limited by the stop pin 18. Rocking plate lever 16 is secured on a shaft 19, journaled in the front wall 11, the outer end of said shaft, carrying a grip or handle 20 by which the shaft may be rocked by the user of the device from the outside thereof.

5 10 Another rocking plate lever 21 is also secured on the inside of the front wall 11, on the opposite side of the chute 12 to that of the plate lever 16, this second rocking lever 21 also having an extension 22, opposite to the coin 14.

15 After having dropped the coin 14 into the position indicated by full lines in Fig. 1, the prospective user will turn the grip or handle 20, and the shaft 19, in a right hand direction, and an upper extension 23 of the plate lever 16 will press the coin 14 against the extension 22 of the plate lever 21 and will rock said lever 21 into its dotted position indicated by 21a, while the 20 lever 16 will take a position 16a, also indicated by dotted lines in Fig. 1.

25 This movement of the two levers will push the coin downwardly, into its dot and dash position 14a, from which position said coin may further drop into an appropriate storage receiver in the machine.

30 A bent flat spring 24 is also secured on the front wall 11, as at 25, its right end 26 normally urging the rocking plate 21 into its normal position, shown by full lines in Fig. 1, the left hand rocking of said lever being limited by the left hand end 27 of the flat spring 24, which in such a position of the plate 21 engages an upper shoulder or step 28 thereon.

35 When the lever 21 is rocked into its position, indicated by the dotted lines at 21a, through the action of the coin 14, it will be kept in such dotted position by the left hand end 27 of said flat spring 24 engaging a second shoulder or step 29 to the 40 left of the shoulder or step 28.

A preferably circular opening or hole 30 is also provided in the front wall 11, as indicated in Figs. 2 and 3, through which may pass a cord or chain 45 31 to the outer end of which is secured a magnifying glass 32 having a handle 33.

50 A sleeve member 34 may be secured on the cord 31, to the rear of the handle 33 of the magnifying glass, having a front flange 35 by which the inward movement of the chain or cord 31 may be limited and also having a preferably partially globular shaped rear flange 36 which may pass through said opening 30, but which in certain positions of the rocking plate lever 21, will be pre- 55

vented from leaving the inside of the casing or housing 10.

Rearwardly of said opening 30, a shaft 37 may be secured in the adjacent side wall 38 of the housing 10 carrying a drum 39 on which the chain or cord 31 is normally wound under the action of the spring 40, pulling the chain 31, and the magnifying glass 32 therewith, into their inward inoperative position, shown in Fig. 2.

10 The use and operation of my device is as follows:

I arrange the housing or casing 10 in any appropriate manner adjacent to the place where a limited use of such a magnifying glass may be desired, like where telephone directories or similar books are kept, possibly in an ill lighted place, and for the better use of which directories may persons would need a magnifying glass, in any case.

20 The cord 31, and the magnifying glass 32 thereon, are withdrawn into their inoperative locking position, the inward movement of the cord being limited by the flange 35, as shown in Fig. 2, and the magnifying glass 32 with its handle 33 hanging downwardly in front of the casing or housing 10.

Following appropriate instructions, the prospective user will drop a coin into the slot 13, which coin will descend in the chute 12 into its 30 position indicated at 14. The user will then turn the grip or handle 20 in a right hand direction and will thereby place the plate levers 16 and 21 into their positions indicated by the dotted lines, at 16a and 21a, respectively, as has been described hereinbefore.

Plate lever 21 in its normal position is in the path of the globular flange 36, the front flat face 36a striking against the portion 41 of said plate lever and normally will prevent a pulling out of 40 the cord 31, preventing a use of the magnifying glass 32. In the dotted position 21a, however, the forward portion 41 of said lever 21 will be lifted or rocked out of the path of the globular flange 36 and now the chain or cord 31 may be 45 drawn out, permitting the use of the magnifying glass 32 within a limited distance from my renting machine.

After the magnifying glass 32 has been used and is released, the cord 31 will be drawn back 50 to its coiled position, shown in Fig. 3, by the action of the spring 40, until the flange 35 will meet the front surface of the front wall 11.

Flat spring 24 also has a cam projection 42 secured thereon (Figs. 1 and 2) and upon its 55 return the globular flange 36 will raise said cam projection 42 and the respective portions of the flat spring 24, lifting it out of engagement with the shoulder 29 in plate lever 21, whereupon said plate lever, under the influence of the end 26 of the spring 24, will return into its normal locking position, shown by the full lines in Fig. 1, preventing a new withdrawal of the cord 31 from the machine as long as a new coin is not dropped thereinto.

65 It may be observed that the globular flange 36 may raise said cam 42 also upon its exit from the casing, thereby placing the plate lever 21 into its normal locking position, but this will not prevent the return of the cord and the globular flange 70 36, since the rear portion 36b of said globular flange is more rounded than the flat front portion 36a thereof, so that upon the return of said globular flange 36 its rear portion is adapted to engage the portion 41 of the plate lever 21, raise 75 the same and slide inwardly thereunder, while,

the outward travel of said flange will be prevented by its flat front surface 36a striking against the portion 41 when the plate lever 31 is in its downward normal locking position, as has been described hereinbefore.

5 In Fig. 2, I indicate, by the dot and dash lines at 43, a protective housing for the magnifying glass 32 and its handle 33, having an open front portion, as indicated at 44, through which the glass may be lifted out of the same, but which housing 43 normally may protect and conceal the same.

10 In Fig. 3, I indicate, by the dot and dash lines at 31a, 32a and 33a, in an imaginary manner and on a smaller scale, the appearance of the 15 cord and the magnifying glass when the same is in use.

To steady the movement of the cord and particularly the globular flange 36, a guide 45 may be arranged on the inside of the front wall underneath the sleeve 34 and globular flange 36.

20 In Figs. 4 to 8, I illustrate another form or embodiment of my invention. In this embodiment also my device may be arranged in a housing or casing, generally indicated by the numeral 25 50, on the inside front wall 51 of which are arranged most of the operative parts of my device, while, a certain portion of them may be arranged on the bottom or floor 52 thereof.

An appropriate receiving opening and guide 30 chute for the coin may be arranged on said front wall, as indicated at 53. The coin 54 will be received between the front wall 51 and a plate 55 secured thereon, and will be held in its position, indicated in Fig. 4, by a flat spring 56 secured 35 on said plate. The termination 57 of spring 56 bent toward the front wall 51, is adapted to yieldingly hold the coin 54 in said position. A shaft 58 is rotatably secured in the wall 51, having a wing, grip or handle 59 on the outside of the casing, while, the major inner portion of said shaft 58 is within the casing. An arm 60 is secured on said shaft, forming a rockable lever underneath the plate 55, that is in the space between said plate and the front wall 51. A loose sleeve 61 is 45 arranged on said shaft beyond the arm 60, said sleeve 61 carrying the peculiarly shaped arms 62 and 63. A spring 64, secured to the bottom of the casing, will normally keep the shaft 58 and the arm 60 thereon in their positions, as indicated in 50 Figs. 4 and 7.

A rocking arm 65 is secured on the bottom 52 of the device, being urged in a clockwise direction by the flat spring 66, secured on a metal frame 67 on the bottom plate 52, as indicated at 68, the 55 clockwise rocking of the arm 65 being limited by a stop pin 70.

The magnifying glass in this embodiment also is secured on a cord or chain 31, similarly as described for the embodiment in Figs. 1 to 3, said 60 cord again carrying a sleeve 34, with a globular flange 36.

Normally the rocking lever 65 swinging around a pin on the bottom 52 of the casing, is in the 65 position shown by full lines in Fig. 5, and in this position the outer end 65a thereof will be in the path of the globular flange 36 and will prevent a withdrawal of the cord 31 by obstructing the path of the flange 36.

70 It is also to be remarked that, in this embodiment, the cord 31 is kept in a withdrawn locked position by a weight 71, slideable in a well 72 in the bottom of the device and secured on the inner end of the cord 31, which cord may be placed 75

around a pulley or roller 73, arranged in the frame 67.

The operation of this embodiment of my device is as follows:

5 After coin 54 is dropped into the position shown in Fig. 4, the shaft 58 will be rocked from the outside, through the wing grip 59, in a right-handed or clockwise direction, whereupon the arm 60 will strike the upper right-hand portion 10 54a of the coin and push said coin, underneath the spring 56, downwardly against the arm 62 on the rockable loose sleeve 61, and in this manner, 15 through the coin 54, said sleeve 61 will be rocked. Arm 63 of said sleeve will now strike the rockable lever 65 on the bottom of the casing, and will 20 set it into its unlocking position, indicated in Fig. 5 by the dotted lines and in Fig. 6 by the full lines. When the arm 65 reaches this position, a 25 flat spring 75 secured over a groove 76 in the bottom 52 of the device, will snap upwardly and its outer end 75a will engage the end 65a of the rock- 30 ing arm 65, and keep said arm in the position indicated by the dotted lines in Fig. 5 and the full lines in Fig. 6, and it will be obvious that the 35 globular flange 36 may now pass said arm 65 and the cord 31, with the magnifying glass thereon, 40 may be drawn out of the casing.

Upon passing outwardly, globular flange 36 through its curved lower surface will gradually 30 press down spring 75 and clear the same from its path. Flange 36 may be formed in such a manner that its upper rear right portion will keep arm 65 from moving forwardly while flange 36 depresses spring 75, as it will be obvious to those versed 35 in this art, but it may also be designed without any such effect in view, in which case arm 65 will be relieved from spring 75 and will follow flange 36 forwardly until said arm is stopped by pin 70, in its normal locking position, as illustrated 40 in Fig. 5.

After the magnifying glass has been used and is released, the cord 31 and the glass thereon, will be withdrawn by the effect of the weight 71, and the globular flange 36 upon its rearward 45 movement will pass over the spring 75, pressing the same into the groove 76, then slightly rocking backwardly the released arm 65 but not sufficiently to be re-engaged by the end 75a of spring 75, and upon being passed in such a 50 manner by the flange 36, said arm 65 will snap back into its full line position (Fig. 5) under the influence of the spring 66, and so prevent a

new withdrawal of the cord 31 unless a new coin is deposited in the chute 53.

The shaft 58 and the arm 60 thereon will be returned to their normal positions by the spring 64, as will be obvious, while the sleeve 61 will be 5 returned by the snapping back of the arm 65, and its action on the arm 63.

A second chute, indicated in Fig. 4 at 77 by the dotted lines, may be arranged underneath the coin 54, terminating in a receptacle 77a in the 10 bottom of the device, and the coin forced through underneath the spring 56 may drop into said chute and said receiver.

A guide device 78 may also be arranged on the 15 bottom of the casing over the flange 36 to guide and steady its motion.

What I claim is new, is:

A coin operated renting device, comprising a closed housing, an extensible member normally withdrawn into said housing, but having one end 20 thereof projecting to the outside through an opening in said housing, a locking device normally preventing a drawing out of said extensible member from said housing, a magnifying glass secured on the outer free end of said extensible 25 member, a coin chute leading to said locking device, means adapted to unlock and release said extensible member by the aid of a coin dropped into said chute and cooperating with said locking device, said means to normally prevent a 30 withdrawal of said extensible member comprising an enlarged portion on said extensible member, a spring pressed rockable plate lever normally obstructing the exit of said enlarged portion from said housing, a second rockable lever, cooperat- 35 ing extensions on said two plate levers adapted to receive the coin between them so that a rocking of said second plate lever will rock said first lever out of its obstructing position and free said extensible member for exit, means to rock said 40 second plate lever from the outside of said housing, means normally urging said first plate lever into its locking position, and means made operative through the rocking of said second plate lever adapted to secure said first plate lever in 45 its open position, said means to secure said first plate lever in such a position being adapted to be made inoperative upon the return of said enlarged portion and said first plate lever permitted to return to its locking position.

FRANK BRODSKY.
